UNITED STATES PATENT OFFICE.

CHARLES BICKMEIER AND DANIEL A. LISTON, OF BELLAIRE, OHIO.

CONTINUOUS-BURNING FURNACE FOR BURNING ENAMEL WARE.

1,140,105.

Specification of Letters Patent.

Patented May 18, 1915.

Application filed October 29, 1913. Serial No. 798,095.

To all whom it may concern:

Be it known that we, CHARLES BICKMEIER and DANIEL A. LISTON, citizens of the United States, residing at Bellaire, in the county of Belmont and State of Ohio, have invented certain new and useful Improvements in Continuous-Burning Furnaces for Burning Enamel Ware, of which the following is a specification.

10 This invention relates to a new and useful improvement in the manufacture of enameled ware and it more especially relates to a continuous burning furnace of enamel ware.

15 The object of the invention is to produce a furnace through which the articles are passed by a continuous movement and with variations in speed; and in which furnace the temperature may remain constant.

20 The invention consists in the construction hereinafter pointed out.

In the annexed drawings: Figure 1 is a plan view of the device, parts similar to those shown being eliminated so as to compress the figure for the purpose of illustration on one sheet. Fig. 2 is a side view, similarly compressed. Fig. 3 is a transverse vertical section through part of the device. Fig. 4 is an enlarged side view of one of the standards. Fig. 5 and Fig. 6 are detail views of parts of the standards. Figs. 7, 8, 9 and 10 are perspective views of the blocks used in forming the top, sides and bottom of the fire box of the furnace.

25 In these drawings the numeral 1 designates the fire box or furnace proper which is placed upon any suitable foundation. This fire box has a base 2, consisting of two sides 3 and 4 set apart, so that there is a space 5 between them the entire length of the base and open at its ends 6 and 7. This base 2 is made of any suitable material and in any suitable way, so as to act as a support for the superstructure. On the tops 8 and 30 9 of the sides 3 and 4 of the base 2 is placed a series or line of blocks 10, such as shown in Fig. 10, side by side, the entire length of the base 2. These blocks 10 have flat flush bottoms 11, sides 12 and ends 13. Their tops 14 have flat topped ribs 15 and channels 16 with downwardly, inwardly sloping sides 17. The width of these blocks 10 is greater than that of the sides 3 and 4 of the base 2. These blocks 10 are placed endwise on top of the sides 3 and 4 of the base 2, so that the

channels 16 of these blocks 10 are alined and form continuous channels the entire length of the furnace on each side thereof. The blocks 10 have their outer edges flush with the outer edges of the sides 3 and 4 and these blocks project inwardly beyond the inner faces of the sides 3 and 4 and partially over the space 5. The blocks 10 of one series on one side of the furnace are spaced apart from the blocks 10 of the other series on the other side of the furnace so that there is a space 18 between the blocks of the two series, this space 18 being open at its ends and connecting with the space 5 between the sides 3 and 4. On top of these blocks 10 at the inner ends of these tops is placed side by side along the furnace on each side a series of cap-like blocks 19, shown in Fig. 9. These blocks 19 have in their bottoms 20, the ribs 21, adapted to fit into the inner channel of the blocks 10 and flat surfaces 22 to fit on flat ribs 15 of the blocks 10. These blocks 19 have at their inner edges top projections 23. The tops 24 of these blocks 19 have the downward and backward curves 25. The projections 23 may extend slightly beyond the inner edges 26 of the blocks 19. The blocks 19 extend beyond the inner edges of the blocks 10, so as to be partially above the space 18. But the projections 23 are to be slightly spaced apart, there being a space 27 between the opposite projections of the two series of blocks 19. This space 27 should be just about sufficient to provide a clear passage for the stems of the standards as will be explained. This space 27 opens downwardly into a space between the lower parts of the ends of the blocks 19 and into the space 18 and the space between the opposite ends of the blocks 19 of the two series is open at its ends. Back of the blocks 19, there is placed endwise upon the tops 14 of the blocks 10 a series of blocks 28, shown in Fig. 8. These blocks 28 have on their bottoms 29 ribs 30 fitting grooves 16 and flat surfaces 31 fitting flat surfaces 15 of the tops 14 of the blocks 10. These blocks 28 also have at their sides interfitting ribs 32 and grooves 33, so that the series of blocks 28 on each side of the furnace will be interlocking and tight-fitting. These blocks 28 also have passing through them the two passages 34 and 35, the object of which will be explained. These blocks 28 have on their tops 36, at the inner ends 37, the upwardly 100

95

110

2
tapering ribs 38, which form continuous tapering ribs, one on each side, at the tops of these blocks 28, the length of the fire box 1. On these ribs 38 rest the cover blocks 39, shown in Fig. 7. These cover blocks 39 have on their under side near their ends 40 transverse tapering grooves 41 adapted to the ribs 38 of the side blocks 28, the ribs fitting into said grooves. At their middles on the underside these blocks 39 have depending transverse tongues 42. On each side of these tongues the bottom face of the blocks 39 has upward and outward curves 43. On top these cover blocks have on the ends the bevels 44.

After the several sets of blocks 10, 19, 28 and 39 are put into place with their several ribs and grooves interlocked, as illustrated in Fig. 3, they are bound together as by end plates 45, with bolts 46 connecting these plates and passing along the bevels 44. At each corner of the furnace is placed a vertical angle plate 47 through the top ends 48 of which angle plates the bolts 46 also pass. At their lower ends 49, these angle plates 47 are braced by rods 50, which are also secured to angle bars 51 embedded transversely in the base 2 of the fire box 1. These bars 51 extend out each side beyond the base 2 of the fire box 1. On these bars 51 on each side of the base 2 are placed the air-supply pipes 52 and gas-supply pipes 53. The air-supply pipes 52 have the inducts 54 provided with valves 55 and adapted for connection with any air supply under pressure. These air-supply pipes 52 have rising from them a number of educts 56 provided with two outlets 57 and 58 leading to and passing partly through the passages 34 and 35 in blocks 28, there being one educt for each such block 28. The gas-supply pipes 53 are to be connected with any gas supply, natural gas or other. These gas-supply pipes 53 have educts 59, as many as there are educts 56, having outlet pipes 60 and 61 which pass through glands 62 and 63 into the outlets 57 and 58 and beyond the inner ends of the latter into the passages 34 and 35.

The construction described produces a furnace having a chamber above, a base below with spaces connected one with another vertically and open at their ends, and pipes for supplying air and gas to the interior of the fire box of the furnace. Into such a device the ware to be enameled is to be continuously passed by the construction now to be described.

An endless track 64 is located in a horizontal plane and so as to pass lengthwise through the space 5 between the sides 3 and 4 of the base. This track 64 is supported upon the beams 51 at its straight portions and at its curved ends 66 and 67 upon suitable pillars 68 and 69, which are firmly braced to support the track and resist strain.

These pillars 68 and 69 rise from suitable base plates 70 and 71, one at each end of the device. The base plate 70 is made adjustable by means of the screw 72 in any usual way for a belt tightener, so that the curved end of the track at this end may be adjusted to take up slack. Stepped into the base plate 71 and rising therefrom is a vertical shaft 73 carrying a worm wheel 74 engaging a worm gear 75 which receives power from the engine 76. Above the worm wheel 74 there is keyed to the shaft 73 a sprocket wheel 77. Stepped into the base plate 70 and rising therefrom is a vertical shaft 78 to which is keyed another sprocket wheel 79. Engaging the teeth of these sprocket wheels 77 and 79 is the endless chain 80, clearly indicated in Fig. 2, as a chain and diagrammatically in Fig. 1. To this chain 80 are secured buggies 81 carrying the standards 82. The buggies 81 consist of a frame 83 having journal bearings 84 in pairs in which fit the journals 85 of rollers 86, and vertical arms 87 for attachment to the chain 80 and the standards 82. To one side of the arm 87 of the buggy 81 is secured a plate 88, having two ears 89 by which the buggy is fastened to the chain 80. The vertical arm 87 of the buggy 81 is made hollow or with three sides and has at the top the threaded hole 90. Into this hole is secured the lower end 91 of the stem 92 of the standard 82. To the top of this stem 92 is secured a three-armed frame 93 from the ends 94 of the arms of which rise fingers 95 having the finely pointed tips 96.

Operation: The articles to be enameled after preliminary preparation are placed, as indicated in Fig. 3, upon the finely pointed tips 96 of the fingers 95. The engine is put into operation and through the worm gear mechanism the sprocket wheel 77 moves the chain 80 and with it the buggies 81, standards 82 and the supported articles upon the standards. As the track 64 with the chain 80 are located in a horizontal plane, the buggies with the standards are always in a vertical position. Gas and air are admitted into the annealing chamber through the outlets 57 and 58 and the outlet pipes 60 and 61, and ignition is made. As the gas and air combined are forced into the annealing chamber, the curved shape of the bottom and top of the annealing chamber causes the flames to take a course indicated by the broken lines in Fig. 3. The curved shape to the bottom and top of the annealing chamber is given in the latter instance by the depending tongues 42, and in the former instance by the projections 23. Hence the flames are thrown both on the outside and the inside of the articles to be burned.

With such a device, the heat within the annealing chamber may be retained constant, and the amount and degree applied to

any article be varied by difference of speed with which the article is passed through the chamber.

Having described our invention, what we claim is:

1. A continuous burning furnace buggy, provided with a frame having a stem rising therefrom, and a standard supported by said stem, such standard having a three-armed frame from the end of the arms of which rise fingers having finely pointed tops.
2. A continuous burning furnace, provided with a top having a depending tongue in the middle, and curves on each side.
3. A continuous burning furnace, having a top provided with a depending tongue in the middle, curves on each side and also provided with a curved bottom.
4. A continuous burning furnace, having a top provided with a depending tongue in the middle, curves on each side of the tongue, and provided with a curved bottom having projections rising from the middle.
5. A continuous burning furnace, having its bottom consisting of two blocks, spaced apart, such blocks having at their inner edges, top projections, and on their tops, curves extending downward and backward from the top projections, and a cover having on the underside a tongue in the middle, and curves on each side of the tongue.
6. A continuous burning furnace, having a chamber, the bottom of which is composed of blocks, spaced apart, and having on top channels and ribs; on top of these blocks, inner and outer blocks having ribs, and flat surfaces fitting the channels and ribs on top of the first blocks, the inner blocks being spaced apart and having at their inner edges, top projections and downward and backward curves, the outer

blocks having on top tapering ribs and a cover having on the underside grooves to fit these tapering ribs and in the middle depending transverse tongues, and on each side 45 of these tongues upward and outward curves.

7. The combination of a chamber, having at its top depending tongues and upward and outward curves on each side of the tongue, and at its bottom projections at the 50 middle, and back of these projections downward and backward curves with passages at top and bottom, leading sidewise into the interior of the chamber, with air and gas pipes provided with educts, an educt from 55 the air supply pipe leading into each passage.

8. A continuous burning furnace, provided with a chamber, having an opening in the bottom and a chain arranged in a horizontal plane, provided with buggies carrying standards for supporting the articles to be burned, such chain passing through the base of the chamber.

9. A continuous burning furnace, provided with a base and a chamber supported thereon, the sides of the base and the sides of the bottom of the furnace being spaced apart; the distance between the sides of the bottom of the furnace being less than between the sides of the base, and a chain arranged in a horizontal plane, provided with buggies carrying standards for supporting the articles to be burned, such chain passing through the base of the furnace. 75.

In testimony whereof we affix our signatures in presence of two witnesses.
